[57] **CLAIM**

The ornamental design for a rectangular thermostat housing with softened corners, as shown and described.

DESCRIPTION

FIG. 1 is an elevation view of the front of the housing; FIG. 2 is an elevation view of the right side of the housing as viewed from the front;

FIG. 3 is an elevation view of the top of the housing; and, FIG. 4 is a perspective view of the housing as viewed from above and to the left.

The rear of the thermostat housing does not comprise any portion of the invention, and hence is not shown in the drawings.

The broken line showing of the time and temperature are for illustrative purposes only and forms no part of the claimed design.
